SPINNING AND DOUBLING MACHINE

Willy Freund, Chemnitz, Germany

Application March 29, 1934, Serial No. 717,924
In Germany April 1, 1933

7 Claims. (Cl. 118—9)

This invention relates to a spinning and doubling machine and has for its purpose to avoid the ballooning which occurs at high speeds of rotation and the injurious strains produced in the yarn by centrifugal effect which hitherto rendered the spinning or doubling of finer yarns impossible. The object of this invention is to render possible the perfect spinning or doubling of yarns up to the finest counts and having low amounts of twist, at the highest spindle speeds. The yarn is produced without ballooning and all undesirable yarn strains are prevented.

The invention is hereinafter described as applied by way of example to a ring or cap spinning machine and consists therein that the yarn arriving from the delivery rollers is passed through a guide eye which is arranged somewhat near the spindle point, the yarn being laid on the spindle point and being so guided in helical turns around the spindle by the aid of projections, that it cannot balloon. The thread is then passed through a yarn brake and connected to the spool tube. The yarn is held at the spindle point, and when necessary or required, is also held at short intervals below the spindle point by means of the said projections over which the yarn is drawn by the pull thereon.

I attain the hereinbefore stated object by the mechanism shown by way of example in the accompanying drawings, wherein—

Figure 1 shows in vertical section a cap spinning device with rising and falling spool.

Figure 2 is a plan view of the cap shown in Figure 1.

Figures 3 and 3a show other forms of the thread brake.

Figures 4 and 5 show another construction with two differently formed heads, the yarn brake being effected by the rising and falling 40 movement.

Figure 4a shows a constructional form in which, as in Figure 4, the removable head and base are cylindrical and both are of smaller diameter than the spool tube to enable the said tube to be placed in position and removed without first removing the head. The extension of the base also serves as a support for the said tube.

Figure 6 shows a head having two rows of yarn 50 controlling protuberances and a neck or contraction below the upper of the said rows.

Figure 7 shows a head which terminates in a point and has one row of yarn controlling protuberances and a contraction.

Figure 8 shows a head having a semispherical

end and one row of yarn controlling protuberances with a contraction beneath it.

Figure 9 shows a head having a flat end and one row of yarn controlling protuberances with a contraction beneath it.

Figure 10 shows a head with a nipple-like end and having two rows of yarn controlling protuberances and a contraction below the upper of the said rows.

Figure 11 shows a head with a completely flattened end and having two rows of yarn controlling protuberances and a contraction beneath the upper of the said rows.

Figure 12 shows a head with two rows of yarn controlling protuberances and a neck.

Figure 13 shows a vertical section of a head with a foundation of hard metal.

Figure 14 shows a cross sectional view of the last named head, taken on a line corresponding with line XIV—XIV of Figure 13.

Figure 15 shows a vertical section of a head with yarn controlling protuberances composed of balls held by a plug.

Figure 16 shows a head of conical form and having yarn controlling protuberances.

Figure 17 shows a head of conical form but with a neck below a row of yarn controlling protuberances.

The device according to Figures 1 to 3a consists of a rotatably mounted spindle 1 on the conical point of which is secured a spinning cap 2, as shown in Figures 1 and 2 or a spinning cap 2a as shown in Figure 3, or a spinning cap 2b as shown in Figure 3a. Above the spinning cap there is provided a vertically adjustable yarn guide 3 through the eye 4 of which is lead the yarn which arrives from the delivery mechanism and is to be spun, the yarn running tangentially from the same to the upper conical end 6 of the cap. The controlling pins 7 are so distributed over the periphery of the cap that the yarn 5 of Fig. 1 or the yarn 5a of Fig. 3 or the yarn 5b of Fig. 3a is controlled by the controlling pins on its way to the lower rim of the cap and guided spirally round the cap periphery. According to Figure 1 the cap is provided at its lower end with an annular hollow 8 which forms an outer cap rim 9 and an inner cap rim 10. The stationary ring 11, which forms a yarn brake due to the nature of its surface, penetrates between the two rims 9 and 10 and is so arranged that the drag produced by it on the yarn 5 is approximately the same on both its outer and inner sides. This is the case when the ring 11 has approximately a radius which is the average between the radii

45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

of the two lower cap rims 9 and 10 and when the ring is formed in cross section symmetrically with the cross sections of the two cap rims 9 and 10. The ring 11 is adjustable vertically which enables the yarn to be wound tightly on the spool with a nearly uniform tension.

The spool tube 12 placed on the spindle 1 is mounted in any suitable manner on a spool rail (not shown) which is displaceable vertically, the spool tube being arranged axially slidable on the spindle 1 by means of a key 13 which causes the tube to be rotated by the spindle. The spool tube 12 serves in known manner to receive a paper tube 14 on which the yarn is wound in the form of a spool 15 by the rising and falling movement of the spool tube and the paper tube.

In the forms of yarn brake according to Figure 3 which can be employed in place of the yarn brake shown in Figure 1, the same consist of the 20 traveller 16 shown in Fig. 3 or the traveller 16b shown in Fig. 3a which is guided on a ring marked 17 in Fig. 3 and marked 17b in Fig. 3a, similarly to ring spinning frames and can be loaded by means of a weight, when required. The traveller ring 25 17 or 17b can either be arranged in a similar manner to the yarn brake ring shown in Figure 1 so that it can be adjusted vertically in the interior of the cap (Figure 3) from below, or enter an 30 annular hollow (Figure 1) in the lower edge of the cap, or it may be arranged beneath the lower edge of the cap (Fig. 3a), the yarn 5b on leaving the periphery of the cap, entering the traveller 16b and being guided by the traveller to the spindle.

35 In the construction according to Figure 4 the spindle a, on which the tube b is slid, is formed at its upper end with a plug c which is adapted to receive a removable head d. The spindle a which requires only to rotate, is driven by means of a 40 warve f. The spindle is surrounded by a guide ring g which is formed and arranged like a spinning ring and carries a traveller h which forms a 45 yarn brake.

The guide ring g is mounted on a ring rail i which is so guided in guides k that it can rise and fall.

The guidance of the yarn is effected by a yarn 50 guide m arranged concentrically above the spindle and preferably adjustable in height. The yarn n is drawn through the traveller h and lies on the 55 peripheral surface of the spindle or the head under the action of the yarn controlling protuberances o or p arranged on the periphery of the head d of the spindle and is guided round the spindle or head by the said protuberances in a spiral coil. The traveller h which forms a 60 yarn brake produces the effect of causing the yarn to be drawn past the protuberances o which are formed more or less flat according to the yarn 65 strength, for example are of lens shape, whilst the guide ring together with the traveller performs the rising and falling movement. In the construction shown in Figure 5 there is a removable head e provided with protuberances p and 70 removably mounted on a plug c' provided on the spindle a³ on which the tube b' is slid. The ring rail, ring and traveller described with reference to Figure 4 is utilized with the construction shown in Figure 5 and also with that shown in Figure 4a.

75 Figure 4a shows the yarn controlling protuberances p' provided on a head d² which enables the tube b² to be placed on and removed without requiring removal of the head d². To this end the head d² and the base d' are of smaller diameter than the internal diameter of the tube b², and

consequently the tube can be merely put on and taken off. The extension d³ of the base is conical and serves as a seat for the tube b². A lower seat for the tube b² is indicated by a'.

The yarn controlling protuberances p' guide 5 the yarn helically in the same manner as that indicated in Figure 4, and the yarn then passes through a similar traveller as the traveller h of Figure 4 before it is wound on the spindle a². Protuberances o' may, as indicated in broken 10 lines, be provided on the base d'.

According to Figures 6 to 12, which show alternative forms of heads for use on the spindle a in place of the removable parts d, e of Figures 4, 5 the heads are provided with an annular hollow such as the hollow q' of Figure 6, or the hollow q² of Figure 7, or the hollow q³ of Figure 8, or the hollow q⁴ of Figure 9, or the hollow q⁵ of Figure 10, or the hollow q⁶ of Figure 11, or the hollow q⁷ of Figure 12, the hollow being 20 situated beneath an upper row of yarn controlling protuberances such as the yarn controlling protuberances o' of Figure 6, or the yarn controlling protuberances o² of Figure 7, or the yarn controlling protuberances o³ of Figure 8, or the yarn 25 controlling protuberances o⁴ of Figure 9, or the yarn controlling protuberances o⁵ of Figure 10, or the yarn controlling protuberances o⁶ of Figure 11, or the yarn controlling protuberances o⁷ of Figure 12, the said hollow serving to lay the 30 yarn on the peripheral surface of the spindle and to guide the same downwardly onto the spindle in a helical coil. In the heads, for example according to Figures 9 and 12, the hollow follows a continuous curve, whereby the yarn lays itself 35 on the spindle or head without cracking. In the constructional form according to Figures 6 and 10 a second ring of yarn controlling protuberances, see the yarn controlling protuberances r' of Figure 6 and the yarn controlling 40 protuberances r⁵ of Figure 10, is shown at the lower edge of the head which in some cases, for example when operating on yarns of certain strengths, form additional means for carrying round the yarn drawn past the hollow. 45

The two-part construction of head according to Figures 13 and 14 has the advantage, in addition to its interchangeability that only the upper part of the head requires to be changed. The head consisting of the two parts 131 and 132 is placed 50 on the spindle 130. The lower, greater, substantially cylindrical part consists of light metal, whilst the upper part 132 provided with the yarn 55 controlling protuberances consists of steel. The part 132 is provided with a four cornered projection 133 by means of which it is engaged with a corresponding socket in the part 131. Naturally, the parts 131 and 132 may be connected together by any other suitable means.

As shown in section in Figure 15, the two-part 60 construction of a head may also serve to enable the rounded or similarly shaped yarn controlling protuberances to be formed on the periphery of the head in a simple manner. The head consisting substantially of a part 134 provided with 65 a projection, and a tubular part 135 is provided with protuberances in the form of balls 136 composed for example of steel and inserted into the radial holes 137 from inside. The balls are gripped tight in the holes 137 which for that 70 purpose are of smaller diameter than the balls and are retained in their correct positions by the stopper 138 which is adapted to be slid from above into position in the tubular part 135. It is of course also possible to secure the balls 136 75

in their holes 137 by forming the holes with somewhat reduced parts at the periphery of the tubular part 135.

Figure 16 shows a two-part head of similar construction to that shown in Figure 15, the part 135a detachably engaging the part 134a. Figure 17 shows a constructionally similar two-part head in which the part 135b detachably engages the part 134b.

10 The shown and described yarn controlling protuberances may be provided on the spindle point itself instead of on a head for mounting on the spindle.

I claim:

15 1. A yarn spinning and doubling machine comprising a rotary spindle, yarn controlling projections rotating with the spindle for guiding the yarn in spiral coils prior to the winding of the yarn on the spindle, in combination with a yarn brake provided on the machine for placing a drag on the yarn and thereby causing the rotary spindle to draw the yarn past the said projections.

20 2. A yarn spinning and doubling machine comprising a rotary spindle, yarn controlling protuberances rotating with the spindle for carrying the yarn round with the spindle and guiding the yarn in a helical, non-ballooned path, in combination with brake means rotating with the spindle for placing a drag on the yarn before it is wound up by the rotary spindle.

25 3. A yarn spinning and doubling machine comprising a rotary spindle, yarn controlling protuberances of rounded form rotating with the spindle for carrying the yarn round with the spindle and guiding the yarn in a helical, non-ballooned path, in combination with brake means rotating with the spindle for placing a drag on the yarn and thereby causing the rotary spindle to draw the yarn past the said projections.

30 4. A yarn spinning and doubling machine com-

prising a rotary spindle, a head provided on the point of the spindle, two annular rows of rounded studs on the head one row of which is situated at the upper end of the head and the other row of which is situated at the lower end thereof and both rows of which are for carrying the yarn round the spindle and guiding the yarn in a helical, non-ballooned path, in combination with brake means rotating with the spindle for placing a drag on the yarn before it is wound up by the 10 spindle.

5 5. A yarn spinning and doubling machine comprising a cap mounted on the spindle point, yarn controlling projections provided on the cap, a tube slidably mounted on and rotating with the 15 spindle for winding on the yarn, a part on the cap which reaches over the said tube and a yarn brake means provided on the machine and situated at the lower end of the cap for braking the yarn on its way from the cap to the said tube. 20

6. A yarn spinning and doubling machine comprising in combination, a spinning or doubling spindle, a tube slidably mounted thereon, a yarn brake member moving round the axis of the said spindle, and yarn controlling protuberances 25 rotating with the spindle for cancelling in conjunction with the yarn brake member, the centrifugal effect acting to produce ballooning of the yarn on its way to the said tube.

7. A yarn spinning and doubling machine comprising a rotary spindle, yarn controlling protuberances rotating with the spindle for carrying the yarn round with the spindle and guiding the yarn in a helical, non-ballooned path, in combination with a revolving and rising and falling guide 35 member capable of a rising and falling movement of equal length to the cap produced by the machine for placing a drag on the yarn before it is wound up by the spindle.

WILLY FREUND. 40
